UNITED STATES PATENT OFFICE.

WASHINGTON I. WOLVERTON, OF ANDERSON, INDIANA, ASSIGNOR TO THE
BUCKEYE MANUFACTURING COMPANY, OF SAME PLACE.

DESIGN FOR A WHIFFLETREE-CLIP MEMBER.

SPECIFICATION forming part of Design No. 34,931, dated August 13, 1901.

Application filed July 3, 1901. Serial No. 67,042. Term of patent 14 years.

To all whom it may concern:

Be it known that I, WASHINGTON I. WOLVERTON, a citizen of the United States of America, residing at Anderson, in the county 5 of Madison and State of Indiana, have invented and produced a certain new and useful Design for a Whiffletree-Clip Member, of which the following is a specification, reference being had to the accompanying drawings, in which—

Figure 1 is a perspective view, Fig. 2 a side elevation, and Fig. 3 a bottom plan view, of my design.

The design consists of a substantially circular plate 1, provided with a central hole 2 and enlarged or extended at one edge to form an arm 3, which turns downward and bends inward to form a hook 4. Rising from arm

3 where hook 4 joins it is an arm 5, which curves inward over the plate 1 and is provided near its extremity with an opening 6, coincident with opening 2, the end of said arm where said hole 6 is formed having formed on it a circular head 8, provided with a circular flattened upper face 7. Connecting hook 4 and arm 5 is a rounded rib 8'.

I claim—

The design for whiffletree-clip member substantially as herein shown and described.

In testimony whereof I hereunto affix my signature, in the presence of two witnesses, this 28th day of June, 1901.

WASHINGTON I. WOLVERTON.

Witnesses:

JAMES F. BOLEN,
HIRAM G. JOHNSTON.
